MEANS FOR SUPPORTING ROTARY CYLINDERS

Filed Nov. 30, 1925

Inventor:
Lucien I. Yeomans,
Bychindell Parker Carlson
Atty.

UNITED STATES PATENT OFFICE.

LUCIEN I. YEOMANS, OF CHICAGO, ILLINOIS.

MEANS FOR SUPPORTING ROTARY CYLINDERS.

Application filed November 30, 1925. Serial No. 72,209.

This invention relates to centrifugal casting machines, rotary driers, cement kilns, and other apparatus comprising cylinders mounted for rotation.

5 In such machines the cylinder is usually supported and confined between rollers, there being a plurality of rollers below the cylinder at each end thereof, and one roller above the cylinder at each end thereof. The 10 invention pertains, in part, to an improved mounting for the lower rollers whereby said rollers are enabled to adjust themselves so that the rollers always bear against the cylinder across the entire periphery of the 15 rollers, and in part to an improved mounting for the top roller.

Referring first to the lower rollers: These are mounted in concave supports so that they may be free to adjust themselves so that 20 the entire face of the roller may bear against the cylinder. Thus, if it should become necessary to reduce the diameter of one of the lower rollers so as to obtain a true surface, all of the lower rollers will be free to 25 swivel or adjust themselves in their concave seats so that all of said rollers have a full bearing upon the cylinder.

In explaining the objects of the invention as it relates to the top rollers, reference may 30 be made to centrifugal casting machines, as, for example, those used in the casting of iron pipes. Because of changes in the diameter of the mold due to temperature changes, it is necessary to mount the top rollers so 35 that they may yield. If the rotating parts be imperfectly balanced the mold will tend to jump, and unless restrained would impose excessive stresses upon the lower supporting rollers. Moreover, when the molten metal 40 is dumped into the rapidly rotating mold, centrifugal force acting upon the fluid metal tends to throw the mold up off the lower supporting roller, and if such rising movement be not restrained the mold will drop 45 back with great force upon the lower supporting rollers and subject said rollers and their ball bearings to excessive stresses. It is therefore necessary to provide means for mounting the top rollers so that they may 50 yield sufficiently to accommodate expansion and contraction of the mold, together with means to prevent the mold from rising off its lower rollers to a material extent.

55 Centrifugal casting machines are sometimes used for casting tubular articles which are of greater diameter at one end than at

the other, and in such instances there is a tendency for one end of the mold to expand or jump more than the other. It is therefore desirable to mount the top rollers so 60 that they may cant slightly in order that they may bear against the mold across the entire periphery of the roller instead of only at one edge of the roller. However, the means to limit yielding movement of the 65 roller must be of such character that if the roller be rising in inclined position it shall not be thrown out of such position by engagement with the movement-limiting means, but on the contrary shall bear across 70 its entire periphery against the mold when stopped by said movement-limiting means.

The object of the present invention, generally stated, is to provide mountings for the lower rollers and the top rollers which 75 shall fulfil the practical requirements hereinbefore stated.

In the accompanying drawings, Figure 1 is a transverse vertical sectional view of a 80 centrifugal casting machine embodying the features of my invention.

Fig. 2 is a view taken in the plane of dotted line 2—2 of Fig. 1.

Fig. 3 is a fragmental view of the top roller on a larger scale than that of Fig. 2. 85

Fig. 4 is a fragmental plan view of the means for supporting the top roller.

Referring first to Fig. 1: The mold A is shown as resting upon and between bottom rollers 1. Each of said rollers is mounted 90 upon a spindle 2 (Fig. 2), ball bearings 3 being interposed between the roller and its spindle. The ends of the spindle are secured in slide blocks 4 which are connected together by a yoke 5. The slide blocks 4 are 95 slidably mounted between guides 6. The lower sides of the slide blocks 4 are convex to conform to concave seats 7. In the construction shown in the present drawings, the seats 7 are formed upon the arc of a circle 100 the center of which normally lies in the axis of the mold A.

It will be seen that the axes of the lower rollers 1 are free to shift so as to enable the rollers to bear against the mold across the 105 entire periphery of each roller.

At each end of the machine there is a head 8 in which a top roller 9 is supported. At opposite sides of the head 8 are formed guideways 10 to receive two slide blocks 11 110 in which the ends of a spindle 12 are secured. Within opposite ends of the hub of

the roller 9 are located two ball bearings 13 by means of which the roller is mounted for free rotation upon its spindle.

The head 8 is provided with a cap 14 having therein two openings 15 in which members 16 in the form of sleeves are mounted for vertical sliding movement. Helically coiled expansive springs 17 are interposed between the blocks 11 and the sleeves 16. On the upper end of each of the sleeves 16 are two bosses 18 having convex upper surfaces which are pressed against concave surfaces on the end portions of an equalizing bar 19 through the action of the springs 17. At its mid-portion the bar 19 is confined by means of a bolt 20 which extends through a central opening 21 in the cap 14 and has a head 22 underlying said cap. The bolt 20 extends freely through an opening 23 in the middle of the equalizing bar, said opening being large enough to allow the bar to tilt. 24 is a washer, 25 an adjusting nut and 26 a lock nut on the bolt 20 above the equalizing bar 19.

25 Plungers 27 bear at their lower ends against the slide blocks 11 and extend freely through the sleeves 16 and into proximity to the ends of the equalizing bar 19. Said bar carries two adjustable stop screws 28 which are alined with the respective plungers 27 and are locked in adjusted position by means of nuts 29.

The extent of movement of the top roller 9 which is necessary to provide for expansion and contraction of the mold is comparatively slight, the stop screws 28 being adjusted to provide the necessary clearance of, say, one-eighth of an inch between the stop screws and the plungers 27 when the roller 9 is in its normal horizontal position.

In operation, the roller 9 is pressed against the mold A by the springs 17. If more pressure be exerted upon one edge of the roller than upon the other, the roller is free to tilt so as to maintain contact with the mold across the entire width of the roller. If, for example, the left-hand portion of the roller should rise, as viewed in Fig. 3, the left-hand slide block 11 will move upwardly. Such movement may continue until the plunger 27 has been forced against the alined stop screw 28, causing the equalizing bar 19 to rock, thereby forcing the right-hand stop screw 28 against the adjacent plunger 27 and thereby pushing the right-hand slide block 11 down until the entire face of the roller bears against the mold. As shown in Figs. 2 and 3, there is sufficient clearance between the slide blocks 11 and the bottoms of the guideways 10 to permit the spindle 12 to rock.

It will be seen that the springs 17, sleeves 16 and equalizing bar 19 constitute yieldable means permitting differential movement of the ends of the spindle 12; that the plungers 27 and stops 28 constitute adjustable means

for limiting the yielding movement of the roller; and that the movement-limiting means is of such character that the roller, if stopped in inclined position, is permitted to remain in such position so as to bear flat 70 against the mold.

As indicated in Fig. 1, the bottom rollers 1 are mounted to rock in planes which are approximately radial of the cylinder A. The top rollers 11 also are mounted for 75 rocking movement in a plane approximately radial of the cylinder. Thus all the rollers are free to accommodate themselves to any slight changes in the position of the cylinder from whatever causes, while at the same time 80 the rollers restrain the cylinder and keep it in proper working position.

I claim as my invention:

1. The combination of a rotary cylinder, supporting means for the cylinder comprising a top roller, and means for yieldably supporting said roller so that it may bear along its entire periphery against the cylinder and permitting differential movement of the opposite ends of the roller, said yieldable supporting means comprising a spindle on which the roller is mounted, slide blocks carrying opposite ends of the spindle, a structure providing guideways for said slide blocks, two sleeves slidably mounted in said structure, coiled expansive springs interposed between said slide blocks and sleeves, an equalizing bar bearing at its ends against said sleeves, a pivotal mounting for the mid-portion of said equalizing bar, plungers bearing against said slide blocks and extending slidably through said sleeves, and adjustable stops carried by said equalizing bar for the ends of said plungers, said stops being normally spaced slightly away from said plungers, and said slide blocks being free to tilt slightly in their guideways.

2. The combination of a rotary cylinder, supporting means for the cylinder comprising a top roller, and means for yieldably supporting said roller so that it may bear along its entire periphery against the cylinder and permitting differential movement of the opposite ends of the roller, said yieldable supporting means comprising a spindle on which the roller is mounted, an equalizing bar, a pivotal mounting for the mid-portion of said bar, means including coiled expansive springs interposed between said spindle and bar, and adjustable means to limit the independent movement of the ends of said spindle.

3. The combination of a rotary cylinder, supporting means for the cylinder comprising a top roller, and means for yieldably supporting said roller so that it may bear along its entire periphery against the cylinder and permitting differential movement of the opposite ends of the roller, said yieldable supporting means comprising a spindle

- on which the roller is mounted, slide blocks carrying opposite ends of the spindle, a structure providing guideways for said slide blocks, two members slidably mounted in said structure, coiled expansive springs interposed between said slide blocks and members, an equalizing bar bearing at its ends against said members and a pivotal mounting for the mid-portion of 30 said bar.
5. The combination of a rotary cylinder, supporting means for the cylinder comprising a plurality of bottom rollers supported for tilting movement, a top roller, and means for yieldably supporting said top roller so that it may bear along its entire periphery against the cylinder and permitting differential movement of the opposite ends of the roller.
10. The combination of a rotary cylinder, supporting means for the cylinder comprising a plurality of bottom rollers supported for tilting movement, a top roller, and means for yieldably supporting said top roller so that it may bear along its entire periphery against the cylinder and permitting differential movement of the opposite ends of the roller.
15. The combination of a rotary cylinder, supporting means for the cylinder comprising a plurality of bottom rollers supported for tilting movement, a top roller, and means for yieldably supporting said top roller so that it may bear along its entire periphery against the cylinder and permitting differential movement of the opposite ends of the roller.
20. The combination of a rotary cylinder, supporting means for the cylinder comprising a plurality of bottom rollers supported for tilting movement, a top roller, and means for yieldably supporting said top roller so that it may bear along its entire periphery against the cylinder and permitting differential movement of the opposite ends of the roller.
25. The combination of a rotary cylinder, supporting means for the cylinder comprising a plurality of bottom rollers supported for tilting movement, a top roller, and means for yieldably supporting said top roller so that it may bear along its entire periphery against the cylinder and permitting differential movement of the opposite ends of the roller.
4. The combination of a rotary cylinder, supporting means for the cylinder comprising a plurality of bottom rollers supported for tilting movement, a top roller, and means for yieldably supporting said top roller so that it may bear along its entire periphery against the cylinder and permitting differential movement of the opposite ends of the roller.
5. The combination of a rotary cylinder, supporting means for the cylinder comprising a plurality of bottom rollers supported for tilting movement, a top roller, and means for yieldably supporting said top roller so that it may bear along its entire periphery against the cylinder, said yieldable means permitting differential movement of the opposite ends of the roller.
6. The combination of a rotary cylinder, lower supporting rollers for the cylinder, a top roller supported for tilting movement and mounted to yield to accommodate expansion and contraction of the cylinder, and means to prevent the cylinder from jumping off the lower rollers, said means being arranged to limit the yielding movement of the top roller, when tilted, without deflecting the roller from such tilted position.
- In testimony whereof, I have hereunto affixed my signature.

LUCIEN I. YEOMANS.
